BOILER AND LIKE FURNACES

Edward M. McNamara, Chicago, Ill.

Application March 23, 1932, Serial No. 600,650

4 Claims. (Cl. 110—40)

This invention relates to that class of steam boiler and like furnaces in which the fire grates of the type which are adapted to gradually shift the mass of burning fuel to the rear of the combustion chamber is combined with a fuel feeding unit at the forward portion of said fire grate and with means for introducing into the mass of fuel adjacent to the fire grate a plurality of supplies of air to attain a proper combustion of the fuel and its volatile elements. And this improvement has for its objects:

To provide in a furnace in which the fire grate is of any usual type adapted to progressively move the mass of fuel from the front to the rear end of the combustion chamber, a formation and combination of parts, especially adapted to effect a very perfect combustion of finely divided bituminous coal, usually the screenings of such form of fuel now generally used in factories and steam heated buildings in the Middle West States on the ground of economy. The said formation and combination comprising a plurality of tubes or conduits open at front and rear ends and extending horizontally through the front wall of the furnace a distance back of said wall into the combustion chamber and located above the fire grate, said open ended tubes being adapted to convey a maximum passage of air into the mass of fuel in the combustion chamber to materially aid in the combustion thereof. The arrangement being such that the portions of the bituminous coal surrounding the plurality of tubes during an ordinary combustion thereof will be partially consumed and its particles caked so that said portions of the fuel in leaving the rear ends of said tubes are formed with a like plurality of tunnels or passages adapted to receive supplies of air from said tubes to materially aid in the combustion of the mass of fuel adjacent to the fire grate, the described formation of said tunnels being maintained and strengthened by a further caking of the particles of fuel forming the wall of the tunnels by local combustion therein until the ash formation period is reached near the rear and discharge end of the rearwardly moving fire grate, all as will hereinafter more fully appear.

In the accompanying drawings:

Fig. 1 is a detail longitudinal section of the front portion of a steam boiler or like furnace having the preferred form of the invention applied thereto.

Fig. 2 is an enlarged detail sectional elevation of one of the air ducts or tubes, means for supporting same and means for effecting vertical adjustment thereof.

Fig. 3 is a detail perspective view of the vertical locking bar by which the supporting means of the air ducts or tubes is secured at the desired adjustment.

Fig. 4 is a detail sectional top view on line 4—4, Fig. 2.

Fig. 5 is a front elevation of the furnace illustrating the transverse arrangement of parts in this invention.

Fig. 6 is an enlarged detail front elevation of a side portion of the same.

Like reference numerals indicate like parts in the several views.

This invention is applicable to any type of furnace having a rectangular combustion chamber 7, the bottom of which is formed by a fire grate 8 of any type adapted to gradually move the burning fuel from the front to the rear end of the combustion chamber.

An ordinary endless chain grate 8 is shown as an exemplification of the above mentioned type of fire grates. The scope of this part of the invention embraces the use instead of said endless chain grate any of the ordinary forms of fire grates in which a gradual rearward shift of the burning fuel towards the rear and discharge end of the fire grate is attained.

In the construction shown in Fig. 1, wherein an endless chain fire grate 8 constitutes the bottom or floor of the combustion chamber, the lower end of the front wall 9 of the furnace ends a short distance above the upper surface of the fire grate to permit the layer of fuel supplied by the fuel feeding hopper hereinafter described, to pass beneath said lower wall end and into the combustion chamber in the rearward movement of the top stretch of said chain grate.

The hopper from which the crushed fuel is fed by gravity to the fire grate 8, is mounted on or adjacent to the front wall 9 of the furnace, and preferably comprises a main upper hopper portion 10, and an open bottom lower chute portion 11 in vertically spaced relation in order to provide for a short passage through the lower mass of fuel in said hopper portion 10 and lower chute portion 11, and on the fire grate 8 of a supply of air to aid in the combustion of the fuel on the adjacent front portion of the combustion chamber.

In the construction shown in Fig. 1, the lower portion of the front wall of the aforesaid chute portion or member 11 is formed by an inclined plate 11' of metal, the lower end of which has separated relation to the top surface of the fire grate 8, so as to provide space for the reception of the hereinafter described air inlet tubes or conduits of this invention. While the rear wall of said chute portion 11 is formed by a vertical portion of the front wall 9 of the furnace, with the lower end of said wall portion having a similar spaced relation to the fire grate as that of the aforesaid inclined front portion 11' of the chute.

A material feature of the invention involves in connection with a furnace construction substantially the same as above described, means for

introducing supplies of air for supporting combustion of the fuel in a even and very effective manner embracing the entire fire grate surface, and to such end comprises a formation and arrangement of parts as follows:—

A longitudinally extending row of air inlet tubes or conduits 12 open at both ends to afford an uninterrupted passage of air to the combustion chamber of the furnace, are associated together in horizontal spaced relation and to such end are fixedly mounted in a carrier head 13, of the plate metal type, and extending the width of the combustion chamber 7 and preferably supported in the adjustable manner hereinafter described by longitudinally arranged bracket plates 14, of the angle type, fixedly attached to the inner faces of the side walls of the furnace. With the described arrangement the plurality of air inlet tubes or conduits 12 are positioned in an approximately horizontal plane a distance above the upper surface of the fire grate 8, with their rear portions extending a distance into the combustion chamber 7 as shown.

Arranged as above described, the plurality of air inlet tubes 12 are adapted to constitute cores for an initial formation of a like plurality of longitudinal air tunnels or passages 15 in the mass of fuel immediately above the fire grate 8.

The initial formation of the air tunnels 15 above mentioned is attained by a partial agglomeration or coherence of the crushed fuel surrounding the tubes 12 during a partial combustion of the same during the ordinary process of combustion in the furnace, and before such portions of the fuel leaves the ends of the tubes 12, while the rear open ends of said tubes are adapted to afford an ample supply of air to maintain local combustion of the walls of said tunnels to more completely agglomerate the walls of the tunnels and maintain such walls intact until the mass of fuel constituting said walls are by gradual combustion reduced to ashes and be discharged at the lower rear portion of the combustion chamber by the supporting fire grate 8, in the progressive rearward travel of the top stretch of said fire grate.

With a view to aid in an effective combustion of the volatile elements of the fuel after the entry thereof into the combustion chamber 7, the sides of the air inlet ducts or tubes 12 are formed with one or more orifices 12' for affording lateral and supplementary supplies of air to the fuel adjacent to said orifices to aid in the combustion of the volatile portions of the fuel.

With a view to prevent entry of particles of fuel into the open rear ends the plurality of air inlet ducts or tubes 12 and consequent interference with the free passages of air therethrough, the rear ends of said ducts or tubes have an oblique or beveled formation as shown, in order that any loose portions of the crushed fuel falling from the rearward overhanging top portions of the tubes 12 will be received on the bottom portions of the tunnels 15 formed in the manner above described in the rearwardly moving mass of fuel, and be carried along with said tunnels and thus prevented from entering the bore of the tubes 12 to impede the free rearward passage of air through the same.

The adjustment of the plurality of air inlet ducts 12 to and from the fire grate 8 is attained in the construction shown in Figs. 1 to 6, by a pivotal rest or engagement of the lower end corners of the inclined plate metal wall 16 of the

carrier head 13 on the bracket plates 14 on the side walls of the furnace, by a notched formation 16' of said lower corners as shown in Fig. 6. And in connection with the above described arrangement of the carrier head 13, a vertically adjustable locking bar 17 is used and which is adapted for manual operation and is formed and arranged as follows:—

The locking bar 17 is arranged for vertical adjustment in the carrier head 13, and is of a flat rectangular shape in cross section and formed with marginal notches 18 adjacent to its respective ends for engagement in rectangular orifices in the top and bottom walls of the carrier head 13, with the lower ends of the locking bars having a rotary bearing in the aforesaid bracket plates 14.

With such construction and with a quarter turn of the locking bars 17 in one direction, locking engagement of the notches 18 of said bar with the rectangular orifices of the carrier head 13 is effected, with such engagement released by a further quarter turn of the locking bars 17.

While natural draft of the furnace and its stack may in many cases be relied on for introducing into the combustion chamber 7 the required amount of air for the proper combustion of the fuel, in many other cases a forced draft may be necessary, and the same can be readily attained by use of the ordinary steam injector nozzles 19, each arranged in central relation to the forward open end of a tube or conduit 12 of the construction shown.

Having thus fully described my invention what I claim as new, is:—

1. The combination in a furnace provided with a combustion chamber, a rearwardly fuel feeding fire grate at the bottom of said chamber, means for feeding crushed fuel to the forward end of said grate, a plurality of air inlet tubes open at both ends and extending through the front wall of said chamber a distance above the fire grate and a distance inwardly from said wall in a position to be wholly enveloped in the entering fuel, the tubes so arranged constituting cores in forming longitudinal air tunnels in the mass of fuel in its progressive movement to the rear of the combustion chamber and with said tubes adapted to supply air for local combustion of the walls of the tunnels, the fire grate being of an endless chain formation.

2. The combination as specified in claim 1, wherein said inlet tubes have their inner open ends of an oblique shape providing upper overhanging end portions adapted to cause the loose fuel particles dropping from the rearwardly overhanging tube portions to drop into the bottom portions of the tunnels so as to be carried rearwardly and prevented from entering the bore of said tubes to impede the flow of air through the tubes into the tunnels.

3. The combination as specified in claim 1, wherein said inlet tubes are provided with means for effecting an adjustment thereof to and from the fire grate.

4. The combination as specified in claim 1, wherein a means for effecting an adjustment of said inlet tubes to and from the fire grate comprising a carrier head adjustably mounted at its rear and lower corner on the furnace housing, and means for locking said head at the required adjustment.

EDWARD M. McNAMARA.
